UNITED STATES PATENT OFFICE.

ROBERT W. SCOTT, OF LEEDS POINT, NEW JERSEY, ASSIGNOR, BY DIRECT AND MESNE ASSIGNMENTS, TO SCOTT & WILLIAMS, INCORPORATED, OF CAMDEN, NEW JERSEY, A CORPORATION OF NEW JERSEY.

KNITTED FABRIC.

1,035,751.

Specification of Letters Patent. Patented Aug. 13, 1912.

Application filed June 8, 1907. Serial No. 377,894.

To all whom it may concern:

Be it known that I, ROBERT W. SCOTT, a citizen of the United States, residing in Leeds Point, Atlantic county, New Jersey, 5 have invented certain Improvements in Knitted Fabrics, of which the following is a specification.

My invention relates to that class of knitted webs, either ribbed or plain, or partly ribbed and partly plain, which have certain wales discontinued, or have wales of one face discontinued and supplanted by wales of the other face, the object of my invention being to prevent "running-back" 15 of the terminal stitches of the discontinued wales.

In the accompanying drawings:—Figures 1 and 2 are exaggerated sectional views of pieces of ribbed fabric illustrating my invention; Fig. 3 is an exaggerated face view of a portion of the web shown in Fig. 1; Fig. 4 is a similar view of a portion of the web shown in Fig. 2, and Fig. 5 is a view 25 similar to Fig. 3 but illustrating a web in which discontinued wales of one face are supplanted by wales of the other face.

Referring, in the first instance, to Figs. 1 and 3 of the drawing, *a* represent the wales of one face of the fabric, for instance 30 those produced by the cylinder needles of a rib knitting machine, and *b* the rib wales or those produced by the dial needles of such a machine, these wales, in the webs illustrated, being those which are intended 35 to be discontinued.

In order to prevent the running back of the terminal stitches *a* of said discontinued wales, I form a chain of said terminal stitches by engaging the terminal stitch 40 of one discontinued wale with that of an adjoining discontinued wale throughout the series, the terminal stitches being elongated for this purpose, as shown, and the final stitch of the series engaging with a 45 rib wale which is not discontinued, as shown in Figs. 1 and 3, or with a wale which, if discontinued, has its terminal stitch *a* merged into an adjoining standing wale, as illustrated in Figs. 2 and 4. This interlooping 50 or enchaining of the terminal stitches of the discontinued wales can be readily effected by employing in connection with the needles on which said terminal stitches are formed, an appropriate looping device

which will engage said terminal stitches in 55 succession, and draw the stitch which it freshly engages through the stitch which is already upon it.

The looper may be carried around the machine by a succession of shogging movements or, by preference, the machine itself may be shogged, so as to bring a looper, located at one spot, into line with the successive wales which are to be discontinued, the needles being retired from action as the 60 65 stitches are removed therefrom. When the last stitch of the series is reached, said stitch, after being drawn through the terminal stitch of the preceding wale, may be either returned to the needle on which it 70 was formed so as to continue the formation of the single rib wale, as shown in Figs. 1 and 3, or may be transferred to the adjoining cylinder needle so as to be merged into the plain wale produced by the latter, as 75 shown in Figs. 2 and 4, or any other available means of retaining the final terminal stitch of the series may be adopted, without removing the web from the broad scope of my invention. 80

In the fabric shown in Figs. 3 and 4 there is no substitute for the discontinued wales, but in the fabric shown in Fig. 5 the discontinued rib wales are supplanted by wales *c* of the other face, these wales 85 being produced by introducing cylinder needles to take the place of the dial needles which have been retired.

My invention is applicable in the production of knitted webs in which change is to 90 be made from ribbed web to plain web, or to webs which are ribbed throughout, but in which the character of the rib in one portion is different from that in another portion, or even to plain webs in which it is 95 desired to reduce the number of wales in one portion as compared with those in another portion.

I claim:—

1. A knitted web having discontinued 100 wales with enchain terminal stitches, the final terminal stitch of the series being engaged with a stitch of a standing wale.

2. A ribbed knitted web having discontinued wales of one face with enchain terminal stitches, the final terminal stitch of the series engaging a standing 105 wale.

3. A ribbed knitted web having discontinued wales of one face with enchain'd terminal stitches, the final terminal stitch of the series engaging a standing wale of 5 the other face of the web.

4. A knitted web, partly ribbed and partly plain, having discontinued wales of one face with enchain'd terminal stitches, the final terminal stitch of the series en- 10 gaging a standing wale.

5. A knitted web, partly ribbed and partly plain, having discontinued wales of one face with enchain'd terminal stitches, the final terminal stitch of the series en- 15 gaging a standing wale of the other face of the web.

6. A knitted fabric, partly ribbed and partly plain, having discontinued wales of one face supplanted by wales of the other

face, the terminal stitches of the discontinued wales being enchain'd and the final terminal stitch of the series engaging a standing wale. 20

7. A knitted fabric, partly ribbed and partly plain, having discontinued wales of 25 one face supplanted by wales of the other face, the terminal stitches of the discontinued wales being enchain'd and the final terminal stitch of the series engaging a standing wale of the other face of the web. 30

In testimony whereof, I have signed my name to this specification, in the presence of two subscribing witnesses.

ROBERT W. SCOTT.
